UNITED STATES PATENT OFFICE.

LAFAYETTE S. SCOTT, OF ROCHESTER, NEW YORK.

ANNUNCIATOR.

No. 876,735.

Specification of Letters Patent.

Patented Jan. 14, 1908.

Application filed December 3, 1906. Serial No. 346,180.

To all whom it may concern:

Be it known that I, LAFAYETTE S. SCOTT, a citizen of the United States, residing at Rochester, in the county of Monroe and State of New York, have invented a new and Improved Annunciator, of which the following is a specification.

This invention relates to annunciators of that class adapted to use upon moving vehicles for indicating successively the different stations along the route and additional thereto advertising matter, as for instance, merely the name of a concern or business house which may be exhibited simultaneously with the name of a street or station, and more especially to that class of annunciators of the character above described which may be applied to and operated automatically on vehicles having a pre-determined path of travel, preferably such as a railway.

In order that any one or more of the names of the stations or the advertising matter exhibited in connection therewith may be changed, either one singly or both together, as desired, I provide a series of character-carrying forms each independently operable by means of elements on the car or vehicle adapted to be engaged and operated by suitable engaging elements disposed along the pathway of the vehicle. In carrying out my invention, I also provide, preferably adjacent to each and every station or pre-determined location for exhibiting a name and sign, a series of tracks located at each such station or stop and on the side thereof adjacent to the next succeeding station in the line of travel of the vehicle or car. I prefer to provide these tracks in two series, the purpose of which will be explained later, and on the car I provide an annunciator comprising a series of independently operable character-carrying forms or wheels in connection with means whereby only one at a time of the characters carried by each form or wheel may be brought into view. For the above reason, I provide, preferably, two actuating mechanisms for each of such forms or wheels independent of the actuating mechanisms for any other ones of such character-carrying forms or wheels. Each of such actuating mechanisms for each of such character-carrying forms or wheels is under the control of a separate element carried also by the car or vehicle and projecting outwardly therefrom and adapted to be engaged and operated by suitable engaging or operating members

properly supported on such tracks in the path of such elements. It is important that all of the character-carrying wheels should have an initial position where they exhibit only a blank.

In the drawings I have shown that embodiment of my present invention adapted to use upon railway cars for indicating successively each next stop or station which the car will make and in connection therewith any brief advertising matter, as for instance, the name of an advertiser in connection with the nearest stop to his place of business which the car will make.

It is obvious that between each element projecting from the car and the corresponding character-carrying wheel or form there should be a suitable connecting mechanism, for which purpose I have found an electromagnet with its armature answers admirably. The source of electric energy and its location are immaterial. By thus providing independent and independently operable character-carrying forms or wheels in the annunciator and the above indicated means for operating such character-carrying wheels, I am enabled first to return all of such wheels to their zero or initial position exposing a blank simultaneously and I am also enabled to advance such wheels simultaneously step by step from their initial positions to the point where there is exposed on each one thereof the proper character in the desired indication to be given by the annunciator. This is a matter of considerable importance, as it is desirable that the annunciator should exhibit the desired information for the maximum possible portion of the period of time which is consumed by the car or vehicle in passing from any one station to the next succeeding station, and this I have found a very important feature in cases where stations are quite near together.

For the sake of avoiding confusion in the drawings and to illustrate more clearly the more essential features of my invention, I have illustrated and described an embodiment thereof comprising only 22 character-carrying wheels arranged in a single row and each of such wheels carrying 37 characters and a blank; the invention, however, is not limited to any particular number of such wheels or any particular number of characters thereon, or yet again to any particular arrangement of the wheels themselves.

The drawings are as follows: -

Figure 1 shows in mechanical diagrammatic view the relation of the tracks at three stations, along the path of travel of such a vehicle, both for returning the letter-carrying form or wheel each to its zero or initial point and for actuating such wheels each from such zero point to the point where they will each expose to view the desired character. Fig. 2 shows in mechanical diagrammatic view the arrangement of the engaging projections on each of the tracks at one of the stations indicated in Fig. 1. In Fig. 2 each of the tracks of each series is shown in side view so as to clearly illustrate the arrangement of the engaging projections thereon and at the left in Fig. 2 the centers of the engaging projections on the tracks are arranged in fine broken vertical lines marked 1 to 38, inclusive, and underneath and engaged by each of the extreme left hand projections on such tracks there is diagrammatically indicated a roller such as is carried by each element projecting from the car, the purpose of which will be explained later. Similarly, to the right, in Fig. 2 there is shown a series of tracks carrying projections adapted, by their engagement with the corresponding elements projecting from the car, to advance the desired one of the character-carrying forms or wheels each to such a point as will result in exhibiting to view in the annunciator the desired indication. Fig. 3 shows in mechanical and electrical diagram the means for actuating any one of the character-carrying forms in such a way as to return the same to its zero or initial position exposing to view a blank thereon. Fig. 4 shows in similar mechanical and electrical diagram the means for actuating any one of the character-carrying forms from the zero or initial position to the position where there will be exposed thereon the proper character in the desired indication. Fig. 5 shows a front view of part of the annunciator with a part of the case removed to show partially the internal arrangement of the parts, while Fig. 6 shows in a similar way a rear view of the annunciator with also a part of the case removed. Fig. 7 shows in interior end view a portion of the upper part of a car with my annunciator in position therein and exposing to view that indication to be given just after passing one of the stations, as will be explained. Figs. 8 and 9 show different views of a modified arrangement of the mechanism comprising the element projecting from the car and adapted to be engaged and operated by the engaging members or projections supported in the pathway thereof upon the tracks, as will be explained.

Refer to Fig. 1.—U—U represent the rails of the railway constituting the pre-determined path of the vehicle. Three cross street stations are indicated diagrammatically, as follows:—Canal St., Worth St. and

City Hall, at each of which stations the vehicle is supposed to stop—the direction of travel is from left to right. A series of tracks T is seen at each station and on the side thereof towards the next succeeding station in the direction of travel, such tracks T being equipped with projections and operating in the manner to be explained to return the character-carrying forms or wheels in my annunciator to the zero or starting point. T¹—T¹ constitute a second series of tracks located at each such station and to the right of the tracks T and also carrying projections and operating, in the manner to be explained, to advance the desired ones of the character-carrying wheels to the point where they will give the desired indication in the annunciator. In Fig. 1 the tracks are shown in diagrammatic plan view and hence the projections on the under side thereof are not shown.

Refer now to Fig. 2.—In this figure there is shown diagrammatically and in side view the tracks T and T¹ with the projections t and t¹ thereon arranged in accordance with the plan and method of operation of my invention in the illustration hereinafter given. A series of rollers a are seen adapted and arranged to be engaged by the projections t carried by the tracks T. To the right of the tracks T are seen tracks T¹, some of which have no projections thereon, while others of them are provided with projections. A series of rollers c are seen as adapted and arranged to be engaged by the projections t¹ on the tracks T¹. The rollers a and c are revolvably supported and carried by the elements projecting from the car and from which they are so supported that as the car travels throughout its pathway or course, the projections t on the tracks T are in the path of the rollers a and the projections t¹ on the tracks T¹ are in the path of the rollers c, as will be explained.

Refer now to Fig. 3.—In this figure there is shown diagrammatically the mechanism and connections between one roller a and its corresponding character-carrying form or wheel. This figure being diagrammatic, all parts are omitted thencefrom except such as are necessary to show the connections between one of such rollers a and its corresponding character-carrying wheel. T represents one of the tracks with the projections t thereon. Z represents a portion of the roof of the car and z a projection carried thereby and arranged transversely of the car. This projection z carries a series of pivotal supports z¹, in each one of which there is pivoted the right hand end of a lever A, the left hand end of which is bifurcated and each such member thus formed is again bifurcated or slotted to engage the ends of a pin extending horizontally through the upper end of the plunger A¹ adapted to move vertically through and

be guided in the opening therefor in the projection b^4 extending upwardly through the roof of the car at the upper left hand corner of the frame B of the annunciator. The lever A carries a clamping socket A¹ within which is secured the lower end of the vertically disposed arm A², on the upper end of which in turn is secured the clamping member A³, in which there is revolubly supported a roller a. This vertically disposed arm A² is sufficiently flexible or elastic to overcome any undue shock or strain upon the apparatus, but it should have sufficient rigidity to force the lever A downwardly to its lowermost position each time that the roller a at the upper end thereof engages a projection t on the track T. The frame work B of the annunciator carries a series of lugs or ears b comprising pivotal supports for the horizontally disposed levers a¹, one only of which is seen in the figure, and between the right hand end of which and the portion b¹ of the frame work of the annunciator a coiled spring a² is seen, operating to force the right hand end of the lever a¹ downwardly and thus raising the left hand end of such lever, which carries with it the plunger A⁴ engaging and resting on the left hand end thereof and therewith also the lever A, and thus operating normally to hold the left hand ends of such levers in their uppermost positions permitted by the washer a⁷ on the plunger A⁴ and opposing the action of the engaging members t on the rollers a. The lever a¹ carries an insulated contact a³, in alignment with which is seen a contact a⁴ carried by the portion b² of the frame work B of the annunciator and extending transversely therethrough. The contacts a³ and a⁴ are normally out of engagement except when, as shown in this figure, the roller a is engaged by one of the projections t on the track T. Supported from the portion b³ of the frame work B is seen an electro-magnet H, the armature of which h is secured to the left hand end of the lever I pivotally supported upon the shaft Y, which extends transversely through the annunciator and parallel with the face thereof. On the under side of the left hand end of this lever I there may preferably be secured a non-metallic strip i adapted to prevent a magnetic contact between the armature h and the core of electro-magnet H. Parallel with the shaft Y there extend through the annunciator rods X and X¹, the function of which will be explained later. To the rod X is secured the lower end of a spring x¹, the upper end of which is secured to a suitable hook depending from the under side of the right hand end of the lever I. The spring x¹ operates to draw the right hand end of the lever I downwardly and to hold the armature h away from the electro-magnet H. On the right hand end of the lever I there is pivotally supported a pawl z¹, the lower end of which is held in engagement with the teeth p on the ratchet wheel P by means of the spring i², operating in the way clearly indicated. A spring x² secured at its left hand end to the rod X and having its right hand end secured to a downwardly extending projection carried by the pawl z, pivotally supported on the rod X¹, operates to hold the pawl z in engagement with the teeth p of the ratchet wheel P in such a way as to prevent a backward rotation thereof. The extreme throw or movement of the lever I is so proportioned relatively to the teeth p of the ratchet wheel P that for each stroke of such lever I the wheel P is advanced one tooth or notch p 70 75 80 85 90 95 100 105 110 115 120 125 130

From a source of electric energy, indicated diagrammatically at U¹, whether the same that propels the car or otherwise is immaterial, a wire 2 leads to the electro-magnet H while the wire 3 leads to the insulated screw connector a⁵ from which a flexible connector leads to the electric contact a³, while from the electric contact a⁴ the wire 1 leads to the other terminal of the coil of the electro-magnet H, whereby it will be seen that each time the roller a engages a projection t on the track T the electro-magnet H is energized by being connected up in a circuit with the source of electric energy U¹, whereby it will also be seen at once that for each one of the projections t on the track T the ratchet wheel P is advanced one notch or tooth p thereon. It should be noted, however, that this ratchet wheel P is not a perfect wheel in that there is a space of one uncut tooth whereby it will at once be seen that such ratchet wheel can be advanced only to the position indicated in Fig. 3 and that any subsequent energizing thereafter of the electro-magnet H will not 100 105 110 115 120 125 130

advance such ratchet wheel P from such position so shown in Fig. 3. This position corresponds to the initial or starting position of the character-carrying wheel connected to the ratchet wheel P in the manner to be hereinafter explained. There is one wheel P and its actuating lever I, an electro-magnet H, a lever A and roller a carried thereby and all the other above described connections between such just above mentioned elements for each and every character-carrying wheel in my annunciator. It will at once be understood then that each of such character-carrying wheels, regardless of its angular position at any one time and the character exposed to view thereon, is returned to the zero or initial position when the car carrying such annunciator passes by or under the tracks T with the engaging members t thereon, such engaging members t on each of such tracks being of course arranged in the pathway of the corresponding roller a carried by the lever A, which comprises one of the two operating elements for each character-carrying wheel projecting from the car.

Refer now to Fig. 4, which shows the mechanism for advancing any one character-carrying wheel from its zero or initial position to the point where there will be exposed 5 to view thereon the desired character. T^1 is a track carrying the engaging projections t^1 . Z is the top of the car, z the projection secured thereon and z^1 the pivotal support for the lever C carrying the socket C^1 for the upwardly-extending arm C^2 , constructed and operating in the same way as the arm A^2 referred to in the description of Fig. 3, and having detachably secured thereto the member C^3 in which is revolubly supported the 10 roller c adapted and arranged to be engaged by the projections t^1 . The plunger C^4 with a washer c^6 thereon is guided in the hole therefore in the portion b^1 of the frame B of the annunciator and is operably connected with the left hand end of the lever C in the same 15 way that the plunger A^4 is connected to the lever A . The lever c^1 is pivoted in the bracket or ear b , two such ears may be used for each lever c^1 if desired, carried by the portion 20 b^1 of the frame B of the annunciator and extending underneath the roof of the car. A spring c^2 operates to force downwardly the right hand end of the lever c^1 , in the manner already described with reference to the lever 25 a^1 , and this lever c^1 carries an insulated contact c^3 from which a flexible connector leads to the connecting screw c^5 . The armature c^1 carries an insulated contact c^4 in alinement with the insulated contact c^4 on the flange b^2 30 on the frame B . An electro-magnet K is supported on the portion b^3 of the frame work B of the annunciator and has one terminal of the coil thereof connected by wire 4 with the contact c^4 . From the other terminal 35 of this electro-magnet K wire 5 extends to the source of electric energy U^1 , which is connected by wire 6 with the contact screw c^6 . The lever J is pivotally supported upon the shaft Y and carries upon its left hand end 40 the armature k in alinement with the core of electro-magnet K . A thin metallic strip j is secured on the under side of the left hand end of the lever J in the same way and for the same purpose as already mentioned regarding 45 the strip i and the lever I . A spring x^2 has its lower end connected to the rod X and its upper end connected to a hook depending from the under side of the lever J near the right hand end thereof. A spring pawl j^1 is 50 pivoted to the extreme right hand end of the lever J and is held in engagement with the teeth p^1 of the ratchet wheel P^1 by means of the spring j^2 secured and operating in the manner clearly indicated in Fig. 4. The 55 ratchet wheel P is also connected with the character-carrying form or wheel revolubly supported upon the shaft W . In Fig. 4 the lower end of the spring actuated pawl j^1 carried by the lever J is seen just at the point of 60 one of the teeth p^1 and just before engaging

the under surface thereof, and the pawl j^1 on the lever I immediately behind it, is seen partially in dotted lines. Immediately behind the ratchet wheel P^1 is seen that portion of the ratchet wheel P comprising the space of the uncut tooth thereon, showing through between the teeth on the wheel P^1 at the upper right-hand side thereof. 70

From the foregoing description it will at once be seen that, each time the roller c engages a projection t^1 on the track T^1 , the electro-magnet K is energized by being connected in circuit with the source of electric energy U^1 . The extreme stroke or throw of the lever J is so proportioned relatively to the teeth p^1 on the ratchet wheel P^1 that each stroke of such lever J operates to advance the wheel P^1 in a clockwise direction one tooth or notch p^1 thereon. The wheels P and P^1 are secured together and preferably 80 on the same end of a spool or two-flanged wheel P^2 . 85

In Fig. 4 a portion of the ratchet wheels P and P^1 are broken away at the center in order to show more fully the construction of 90 the character-carrying wheel or form P^2 secured thereto, such wheel P^2 comprising two flanges p^2 , one only of which being the one next to the observer is seen. Each of the flanges p^2 has a series of holes therethrough 95 near the outer edge in which there are pivotally supported the inner ends of the character-carrying flaps Q , the outer ends of four of which are seen as supported upon the ledge e just within the face of the annunciator, and practically at right angles with the lower one of which is seen the first or exposed one of several others of such flaps Q occupying practically vertical positions. As the wheel P is actuated or advanced one notch or tooth, at 100 a time, by the energizing of the electro-magnet K , the different successive ones of the flaps Q are brought into view, exposing the character thereon. Of these character-carrying flaps Q there are provided on each 110 wheel one for each character within the range of characters called for by the indications which it is desired to give and also a blank flap. The number of such flaps then, in accordance with the scheme outlined in 115 Figs. 1 and 2, will be 38, including such blank. As the starting point for each wheel is that point where it shows the blank, there is necessitated only 37 projections t^1 on the track T^1 in order to bring into view successively each character thereon, the first and last of such projections, operating to bring into view "A" and " " respectively, and between these extremes any desired character may be brought into view on any one wheel 120 at any station according to the number of projections t^1 on the track T^1 at that station. 125 As seen in Figs. 5 and 6, I prefer to arrange a track T and a track T^1 , with the projections t and t^1 thereon respectively, adja- 130

cent to each other and to arrange the rollers *a* and *c* and the supporting levers *A* and *C* similarly adjacent to each other and the corresponding ratchet wheels *P* and *P'* respectively adjacent to each other and at one and the same end of the flanged wheels or spools *P* and *P'* with the wheel *P'* to the left or outside of the wheel *P*.

Refer now to Figs. 4 and 7,—near the top and across the face of the annunciator is seen a transparent sheet *E*, preferably of glass, behind which there may be suitably supported and exposed to view an opaque sheet *E'* having cut out therefrom the letters comprising the words "The next stop is". It is quite immaterial how this indication is secured provided that it is permanent and is legible by daylight and also by a light, such as the incandescent lamp *k'*, suitably arranged and supported within the annunciator, as indicated in Fig. 5. As the flaps *Q* are pivoted at their inner ends within the flanges of the wheel *P*, the outer edge of each one describes practically a quarter of a circle as it falls from the ledge *e* and just as it comes into view. It is important then that there be suitably supported beneath the transparent sheet *E* a transparent sheet *F* which may preferably be bent to conform approximately to a quarter of a cylinder, the axis of which coincides with or passes through the pivotal supports for those flaps *Q* which are at any one time exposed to view. The plates *E*, *E'* and *F* comprising non-essential features of my present invention, the details of their construction will not be further described. It is very important, however, that the inner edge of the ledge *e* be straight and parallel with the alined pivotal supports for such of the flaps *Q* as are at any one time exposed to view, and also that the inner edge of such ledge *e* be arranged relatively to the shaft *W* and the character-carrying wheels revolvably supported thereon substantially as shown in Fig. 4.

Refer now to Fig. 7,—in this figure the annunciator is shown as giving the proper indication after the car has passed the tracks *T'* located on the right hand side of the Canal St. station, as indicated in Fig. 1, and this indication stands or remains until the rollers *a* carried by the levers *A* are engaged by projections *t* on the tracks *T* at the right hand or down town side of the Worth St. station, and thereafter the rollers *c* on the proper levers *C* are engaged by projections *t'* on the corresponding tracks *T'* at the right hand or down town side of the Worth St. station in such a way as to cause the annunciator to give the next desired indication, the character and nature of such operation being substantially the same as already described in reference to the indication caused to be given by the annunciator just after leaving Canal St.

I desire to call attention to the fact that the electro-magnets *H* and *K* and their armatures *h* and *k* respectively are shown only diagrammatically as well as the electric connections with the coils of such electro-magnets. In practice, I prefer to make use of an electro-magnetic construction in which the only break in the magnetic path comprises the operative stroke of the armature to and from the core of the electro-magnet, such and other details of construction comprising non-essential features of my present invention, are indicated only in diagram. When more than one annunciator is made use of in a car, that is, one at each end, or when several annunciators are used on different cars, it will of course be understood that such connections will be made between the source of electric energy and the coils of the electro-magnets in such different annunciations as will result in simultaneously operating the corresponding character-carrying wheels in all of such annunciations, whereby all of such annunciations will simultaneously give the same indication to an observer facing them, and it is quite immaterial what system of connections is resorted to for securing this end.

Refer now to Figs. 8 and 9 which show different positions of the parts of a modified arrangement of a projecting element or lever carrying rollers adapted to be engaged by projections *t* on a track *T*, or *t'* on a track *T'*. *Z* is part of the roof of the car, *B* a part of the frame work of the annunciator beneath the same, *z* the projection carried by the roof of the car *Z* and comprising a seat for receiving the pivotal supports *z'* for the lever *N*, on which at its upper left hand end there is pivotally supported the three-armed lever *N'*, on each of the two upper arms *n* of which in turn there is pivotally supported a roller *a*, at such a distance apart as to at least span the space on the track *T* covered by one of the projections *t*. The lever *N* carries at its upper left hand end also the horizontally movable and spring actuated plungers *n*⁵, operating to hold the downwardly extending arm *n*⁴ of the three-armed lever *N'* in a central vertical position practically such as seen in Fig. 8, which is the normal position for the parts, except as one of the rollers *a* carried by the horizontal arms *n* on this lever *N'* is engaging by a projection *t* on the track *T*. Check nuts *n*⁶ are provided on the outer ends of the plungers *n*⁵ to limit, their movement and the springs maintain the adjustment of the parts to the normal positions just above described. Between the lower arm *n*⁴ of this lever and the upper end of the bell crank lever *n*³ there is pivotally secured the connecting rod or link *n*². The lever *n*³ is pivotally supported in an ear or lug *z*³, and of these ears *z*³ there may be, if desired, 130

two for each of such levers n^3 , and they are secured, preferably, to the frame B of the annunciator in any suitable way not shown. The left hand end of the horizontal member of the bell crank lever n^3 is bifurcated and is connected to the plunger A^4 , having the washer a^6 thereon and working through the projection b^4 carried by the frame work b of the annunciator, in substantially the same manner as already fully described in referring to Figs. 3 and 4 in regard to the connections between the plungers A^4 and C^4 and the bifurcated ends of the levers A and C respectively. The lever N has an arm n^4 extending to the right from its pivotal support, such extension carrying a downwardly extending stop adapted to engage the upper surface of the horizontal plate carrying the ears z^2 to prevent the spring s from forcing the left hand end of the lever n upwardly beyond the proper limit therefor. The arm n^4 on the lever N carries a hook adapted to be engaged by the upper end of the spring s , the lower end of which is secured to the top of the car Z^1 and tends to hold the lever N in the position indicated in Fig. 8, with the roller a , on the three-armed lever N^1 pivoted thereon, firmly up against the under side of the track.

In Fig. 9 the parts are shown in the position which they assume when the right hand roller a is engaged by and opposite the center of one of the projections t on the track T, for which position it will be seen that the plunger A^4 has been forced downwardly so that the washer a^6 thereon rests upon the upper surface of the projection b^4 carried by the frame of the register B.

It will be seen at once by reference to Figs. 8 and 9 that the position of the plunger A^4 , whether up or down, is dependent, quite entirely upon the angular disposition of the three-armed lever N^1 regardless, within the moderate range called for by variations in the load on the car, of the height of the left hand end of the pivotal support for this three-armed lever N^1 pivoted at the upper left hand end of the lever N.

I have found it desirable to make use of the arrangement just described to compensate for variations in the load on the car in order that the position of the plungers A^4 and C^4 may be dependent upon the engagement of the rollers a and c by the projections t and t' respectively, and independent of the height of the pivotal support for the levers carrying such rollers as affected or modified by the load on the car.

The foregoing detailed description of the construction and operation of the different features and parts of my annunciator it is believed, sufficiently explains the operation of my annunciator to make further description thereof unnecessary herein. I will add, however, that when it is desired to change the

indication given by the annunciator it is only necessary to change the arrangement of the projections t' on the tracks T at that station preceding the one for which the desired changed indication is to be made. It will of course be understood that on each series of such tracks T and by means of the projections t' on the individual tracks in such series there is spelled out, in the manner clearly above indicated, the desired indication to be given. 75

I desire to call attention to the fact that the pawls i^1 , j^1 and x constitute means for preventing a backward rotation of the character-carrying forms, while the pawls i^1 and j^1 , when at rest, have a strong tendency to hold such character-carrying forms in a position exposing either a blank or a character thereon; also to the fact that the uncut space of one tooth on the ratchet wheel P on each such character-carrying form comprises means for preventing a movement of each character-carrying form, when at its zero or initial position, by the electrically controlled mechanism arranged to be actuated from the battery U each time that the projecting operating element comprising the lever A and the arm A^2 and roller a thereon is engaged and operated by a member t in the path thereof. 85

What I claim is:— 95

1. The combination with a vehicle having a predetermined path of travel of an annunciator on said vehicle comprising, a series of independent and independently operable character-carrying forms each having a series of characters thereon, a case adapted to expose to view in legible arrangement one character only at a time on each form and means tending to hold each form with either a blank or a character thereon exposed to view; an independent operating element for each such form carried by and projecting outwardly from such vehicle; a member at each predetermined point where it is desired to change the indication given by the annunciator arranged in the pathway of each projecting operating element corresponding to a character form to be advanced and for each step or space of one character thereon which such form is to be advanced to give the desired next indication, each said member being adapted to engage and operate such projecting element and connections between each projecting operating element and corresponding character-carrying form whereby as each such element is engaged by a member in the path thereof the corresponding form is advanced to expose the next character thereon. 115

2. The combination with a vehicle having a predetermined path of travel of an annunciator on said vehicle comprising, a series of independent and independently operable character-carrying forms each having a series 130

of characters thereon, a case adapted to expose to view in legible arrangement one character only at a time on each form and means tending to hold each form with either a blank or a character thereon exposed to view; an independent operating element for each such form carried by and projecting outwardly from such vehicle; a member at each predetermined point where it is desired to change the indication given by the annunciator arranged in the pathway of each projecting operating element corresponding to a character form to be advanced and for each step or space of one character thereon which such form is to be advanced from its zero or initial position to give the desired next indication, each said member being adapted to engage and operate such projecting element; connections between each projecting operating element and corresponding character-carrying form whereby as each such element is engaged by a member in the path thereof the corresponding form is advanced to expose the next character thereon and means for returning to its initial position each character-carrying form not already at such initial position before each such advancement therefrom to give such desired changed indication.

3. The combination with a vehicle having a predetermined path of travel of an annunciator on said vehicle comprising, a series of independent and independently operable character-carrying forms each having a series of characters thereon, a case adapted to expose to view in legible arrangement one character only at a time on each form and means tending to hold each form with either a blank or a character thereon exposed to view; two independent operating elements for each form carried by and projecting outwardly from such vehicle; a member at each predetermined point where it is desired to change the indication given by the annunciator arranged in the path of the first one of each such pair of projecting operating elements corresponding to a character form to be returned to its zero or initial position and for each space or step of one character thereon which the form is to be moved to return the same to its zero or initial position, each said member being adapted to engage and operate such first projecting element, and at each such predetermined point a member arranged in the path of the second one of each such pair of projecting operating elements corresponding to a character-carrying form to be advanced from its zero or initial position and for each step or space of one character thereon which such form is to be advanced from such zero or initial position to give such changed indication, each said last named member being adapted to engage and operate such first projecting element, and at each such predetermined point a member arranged in the path of the second one of each such pair of projecting operating elements corresponding to a character-carrying form to be advanced from its zero or initial position and for each step or space of one character thereon which such form is to be advanced from such zero or initial position to give such changed indication, each said last named member being adapted to engage and operate the second one of such pair of projecting operating elements; connections between the first one of each such pair of projecting operating elements and the corresponding character-carrying form whereby as such first element is engaged by a member in the path thereof the corresponding form is moved the space of one character thereon until and only until the zero or initial position thereof is reached and connections between the second one of each such pair of projecting operating elements and corresponding form whereby as such second element is engaged by a number in the path thereof such form is advanced to expose the next character thereon.

4. The combination with a vehicle having a predetermined path of travel of an annunciator on said vehicle comprising, a series of independent and independently operable character-carrying forms each having a series of characters thereon, a case adapted to expose to view in legible arrangement one character only at a time on each form and means tending to hold each form with either a blank or a character thereon exposed to view; two independent operating elements for each form carried by and projecting outwardly from such vehicle; a member at each predetermined point where it is desired to change the indication given by the annunciator arranged in the path of the first one of each such pair of projecting operating elements corresponding to a character form to be returned to its zero or initial position, the number of members in said series equal to or more than the number of steps or spaces of one character thereon which such form is to be moved to return the same to its zero or initial position, each said member adapted to engage and operate such first projecting element, and at each such predetermined point a member arranged in the path of the second one of each such pair of projecting operating elements corresponding to a character form to be advanced to expose the next character thereon.

5. The combination with a vehicle having a predetermined path of travel of an annunciator on said vehicle comprising, a series of independent and independently operable character-carrying forms each having a series of characters thereon, a case adapted to expose to view in legible arrangement one character only at a time on each form and means tending to hold each form with either a blank or a character thereon exposed to view; two independent operating elements for each form carried by and projecting outwardly from such vehicle; a member at each predetermined point where it is desired to change the indication given by the annunciator arranged in the path of the first one of each such pair of projecting operating elements corresponding to a character form to be returned to its zero or initial position, the number of members in said series equal to or more than the number of steps or spaces of one character thereon which such form is to be moved to return the same to its zero or initial position, each said member adapted to engage and operate such first projecting element, and at each such predetermined point a member arranged in the path of the second one of each such pair of projecting operating elements corresponding to a character form to be advanced to expose the next character thereon.

6. The combination with a vehicle having a predetermined path of travel of an annunciator on said vehicle comprising, a series of independent and independently operable character-carrying forms each having a series of characters thereon, a case adapted to expose to view in legible arrangement one character only at a time on each form and means tending to hold each form with either a blank or a character thereon exposed to view; two independent operating elements for each form carried by and projecting outwardly from such vehicle; a member at each predetermined point where it is desired to change the indication given by the annunciator arranged in the path of the first one of each such pair of projecting operating elements corresponding to a character form to be returned to its zero or initial position, the number of members in said series equal to or more than the number of steps or spaces of one character thereon which such form is to be moved to return the same to its zero or initial position, each said member adapted to engage and operate such first projecting element, and at each such predetermined point a member arranged in the path of the second one of each such pair of projecting operating elements corresponding to a character form to be advanced to expose the next character thereon.

- independent and independently operable character-carrying forms each having a series of characters thereon, a case adapted to expose to view in legible arrangement one character only at a time on each form and means tending to hold each form with either a blank or a character thereon exposed to view; an independent electrically controlled mechanism for advancing each form the space of one character thereon at a time; a source of electric energy; an independent operating element carried by and projecting outwardly from such vehicle for each such independent electrically controlled mechanism; a member at each pre-determined point where it is desired to change the indication given by the annunciator arranged in the path of each projecting operating element corresponding to a character form to be advanced and for each step or space of one character thereon which such form is to be advanced to give the desired next indication, each said member being adapted to engage and operate such projecting element and means whereby each such electrically controlled mechanism is actuated from such source of electric energy once as each corresponding projecting operating element is engaged by a member in the path thereof.
6. The combination with a vehicle having a predetermined path of travel of an annunciator on said vehicle comprising, a series of independent and independently operable character-carrying forms each having a series of characters thereon, a case adapted to expose to view in legible arrangement one character only at a time on each form and means tending to hold each form with either a blank or a character thereon exposed to view; an independent electrically controlled mechanism for advancing each form the space of one character thereon at a time; a source of electric energy; an independent operating element carried by and projecting outwardly from such vehicle for each such independent electrically controlled mechanism; a member at each predetermined point where it is desired to change the indication given by the annunciator arranged in the path of the first one of each pair of projecting operating elements corresponding to a character form to be returned to its zero or initial position and for each space or step of one character thereon which the form is to be moved to return the same to its zero or initial position, each said member being adapted to engage and operate such first projecting element, and at each such predetermined point a member arranged in the path of the second one of each such pair of projecting operating elements corresponding to a character-carrying form to be advanced from its zero or initial position and for each step or space of one character thereon which such form is to be advanced from such zero or initial position to give such changed indication, each said last named member being adapted to engage and operate the second one of such pair of projecting operating elements and means whereby such first and second electrically controlled mechanisms are each actuated respectively each time that such first and second projecting operating elements are engaged and operated by members in the paths thereof.
7. The combination with a vehicle having a predetermined path of travel of an annunciator on said vehicle comprising, a series of independent and independently operable character-carrying forms each having a series of characters thereon; a case adapted to expose to view in legible arrangement one character only at a time on each form and means tending to hold each form with either a blank or a character thereon exposed to view; two independent electrically controlled mechanisms for advancing each form the space of one character thereon at a time; a source of electric energy for such electrically controlled mechanisms an independent operating element carried by and projecting
- such advancement therefrom to give such desired changed indication.
8. The combination with a vehicle having a predetermined path of travel of an annunciator on said vehicle comprising, a series of independent and independently operable character-carrying forms each having a series of characters thereon, a case adapted to expose to view in legible arrangement one character only at a time on each form and means tending to hold each form with either a blank or a character thereon exposed to view; two independent electrically controlled mechanisms for advancing each form the space of one character thereon at a time; a source of electric energy for such electrically controlled mechanisms an independent operating element carried by and projecting

outwardly from such vehicle for each such independent electrically controlled mechanism; a series of members at each predetermined point where it is desired to change the 5 indication given by the annunciator arranged in the path of the first one of each such pair of projecting operating elements corresponding to a character form to be returned to its zero or initial position, the 10 number of such members in said series equal to or more than the number of steps or spaces of one character thereon which such form is to be moved to return the same to its zero or initial position, each said member being 15 adapted to engage and operate such first projecting element, and at each such predetermined point a member arranged in the path of the second one of each such pair of projecting operating elements corresponding 20 to a character-carrying form to be advanced from its zero or initial position and for each step or space of one character thereon which such form is to be advanced from such zero or initial position to give such changed indication, each said last named member being 25 adapted to engage and operate the second one of such pair of projecting operating elements; means whereby such first and second electrically controlled mechanisms are each 30 actuated each time that such first and second projecting elements are engaged and operated by members in the paths thereof and means whereby a movement of each character-carrying form when at its zero or initial 35 position by that electrically controlled mechanism actuated from the source of electric energy by the engagement of the first one of the corresponding pair of projecting operating elements by members in the path thereof, 40 is prevented.

9. The combination with a vehicle having a predetermined path of travel of an annunciator on said vehicle comprising, a series of independent and independently operable 15 character-carrying forms each having a series of characters thereon, a case adapted to expose to view in legible arrangement one character only at a time on each form and means tending to hold each form with either 20 a blank or a character thereon exposed to view; an independent operating element carried by and projecting outwardly from such vehicle for each such independent electrically controlled mechanism; a member at each predetermined point 25 where it is desired to change the indication given by the annunciator arranged in the path of each projecting operating element corresponding to a character form to be advanced and for each step or space of one character thereon which 30 such form is to be advanced to give the desired next indication, each said member 35 being adapted to engage and operate such projecting element and connections between each projecting operating element and corresponding character-carrying form whereby 40 as each such element is engaged by a member in the path thereof the corresponding form is advanced to expose the next character thereon, all of such projecting operating elements corresponding to character forms to 45 be advanced at any such predetermined point adapted to be engaged and operated at approximately the same time by members in the pathways thereof whereby all of such character-carrying forms may be advanced 50 simultaneously throughout a portion of their movement.

10. The combination with a vehicle having a predetermined path of travel of an annunciator on said vehicle comprising, a series of 55 independent and independently operable character-carrying forms each having a series of characters thereon, a case adapted to expose to view in legible arrangement one character only at a time on each form and means tending to hold each form with either 60 a blank or a character thereon exposed to view; an independent electrically controlled mechanism for advancing each form the space of one character thereon at a time; a 65 source of electric energy; an independent operating element carried by and projecting outwardly from such vehicle for each such independent electrically controlled mechanism; a member at each predetermined point 70 where it is desired to change the indication given by the annunciator arranged in the path of each projecting operating element corresponding to a character form to be advanced and for each step or space of one character thereon which such form is to be advanced to give the desired next indication, each said member being adapted to engage and operate such projecting element and means whereby each such electrically controlled mechanism is actuated from such 75 source of electric energy once as each corresponding projecting operating element is engaged by a member in the path thereof, all of such projecting operating elements corresponding to character forms to be advanced at any such predetermined point adapted to be engaged and operated at approximately the same time by members in the pathway thereof whereby all of such character-carrying forms may be advanced simultaneously 80 throughout a portion of their movement.
